UNITED STATES PATENT OFFICE.

SOLON SMITH, OF KREBS, OKLAHOMA.

REMOVABLE COVER FOR RECEPTACLES.

1,168,122.

Specification of Letters Patent. Patented Jan. 11, 1916.

Application filed April 11, 1914. Serial No. 831,302.

To all whom it may concern:

Be it known that I, SOLON SMITH, a citizen of the United States, residing at Krebs, in the county of Pittsburg and State of 5 Oklahoma, have invented certain new and useful Improvements in Removable Covers for Receptacles, of which the following is a specification, reference being had to the accompanying drawings.

10 This invention relates to new and useful improvements in receptacles and more particularly to what will be known as a miner's dinner pail, the main object of the invention being the provision of an improved means 15 whereby the cover of a miner's dinner pail can be quickly and readily placed in position and, at the same time, will be securely held against accidental removal.

Another object of the present invention 20 is the provision of an improved cover for miners' dinner pails or buckets which will possess advantages in points of efficiency and durability, is inexpensive to manufacture and, at the same time, is simple in construction and operation.

With the above and other objects in view, the invention consists in the novel features of construction, combination and arrangement of parts as will be hereinafter referred 30 to and more particularly pointed out in the specification and claim.

In the accompanying drawing forming a part of this application, Figure 1 is a vertical sectional view of a receptacle constructed 35 in accordance with my invention. Fig. 2 is a transverse sectional view through the upper deck member. Fig. 3 is a transverse section taken on the line 3—3, Fig. 1; and Fig. 4 is a detail elevation illustrating the 40 relative position of the slot and pin.

It is a well known fact that miners' dinner pails generally consist of a body portion which, in the accompanying drawing is indicated by the numeral 1 and which is particularly adapted for the reception of tea, coffee, soups or any other liquid eatables which the owner of the bucket might desire to carry. This body 1 of the bucket is provided upon opposite sides with the usual 45 ears 2 to which the ends of the pail 3 are secured, said pail supporting the handle 4 at its medial portion whereby the bucket 50 may be readily carried about.

Arranged within the upper end of the

body of the bucket is what is known as a 55 deck or second receptacle, which is indicated by the numeral 5 and is especially adapted for the solid food and is to be removably arranged within the upper end of the body. As a general rule, these decks or 60 receptacles 5 are frictionally supported within the body 1, while in the present instance, the body 1 is provided with an annular supporting flange 6, upon which the lower end of the receptacle 5 is adapted to 65 rest to support the same within the body. The side walls of the receptacle 5 are slightly inclined and are provided upon the inner side adjacent the upper edge of the receptacle with the opposed lugs 7 which project 70 inwardly into the body of the receptacle. The upper open end of the receptacle 5 is closed by means of a removable cover 8 having a suitable handle 9 formed thereon, whereby the cover may be quickly and 75 readily placed in position or removed from the top of the receptacle. The cover 8 is provided with a downwardly and inwardly inclined annular flange 10, the outer surface of which is preferably ground, the purpose 80 of which will be hereinafter more fully set forth.

The annular flange 10 of the cover 8 is provided at diametrically opposite points with the opposed bayonet slots 11, which 85 include the vertical portions 12 and the horizontal portions 13. Thus, when the cover is arranged in position upon the receptacle 5, the vertical portions of the slots 11 are adapted to receive the lugs 7 and after the 90 cover has been pressed downwardly until the outwardly projecting flange 14 engages the upper edge of the receptacle 5, the cover is turned until the slots 7 are disposed within the horizontal portions 13 of the slots 11 95 and, in view of the fact that the outer face of the flange 10 is provided with a ground surface, it will tend to engage with the ground surface which is preferably formed upon the inner face of the receptacle 100 5 at the upper end thereof and prevent any accidental movement of the cover 8 which would tend to disengage the pins or lugs 7 from the horizontal portions of the slots 11 and thus release the cover from its closed 105 position.

From the above description taken in connection with the accompanying drawing, it

will be readily apparent that I have provided a simple and durable dinner bucket wherein the cover thereof is securely retained in a closed position and held against 5 accidental removal of the same and it is to be understood that while I have shown and described my improved adjustable cover as applied to a dinner bucket, it will be apparent that the same may be used equally 10 as well upon milk cans or any other similar containers.

My device, as herein shown and described, is extremely simple in construction and can be manufactured and placed upon the 15 market at a comparatively low cost.

While I have particularly described the preferred embodiment of my invention, it will be obvious that various changes in the details of construction and in the proportions 20 may be resorted to for successfully carrying my invention into practice, without sacrificing any of the principles of the invention, or departing from the scope of the appended claim.

Copies of this patent may be obtained for five cents each, by addressing the "Commissioner of Patents, Washington, D. C."

Having thus described this invention, 25 what I claim is:—

A receptacle including an outer body having an annular internal flange spaced above its bottom wall, an inner receptacle freely insertible in the outer receptacle, said inner 30 receptacle being of less length than the outer receptacle, whereby its lower end seats upon the flange, a removable closure for the inner receptacle, said closure being provided with a depending annular flange which seats 35 within the inner receptacle, fastening means whereby the flange of the closure may be detachably engaged with the inner receptacle, and a handle for the closure, said handle being adapted to be grasped to thereby remove 40 the inner receptacle from the outer receptacle.

In testimony whereof I hereunto affix my signature in the presence of two witnesses.

SOLON SMITH.
